UNITED STATES PATENT OFFICE

WILLIAM S. EATON, OF SAG HARBOR, NEW YORK

CHROMIUM-PLATING MACHINE

Application filed October 28, 1926. Serial No. 144,678.

My invention relates to chromium plating machines, and more particularly to a construction and arrangement of parts which will present, in compact form, all of the agencies required in carrying on the plating operation under conditions which will avoid likelihood of injury to the user of the machine.

With a machine embodying the invention, the plating operations may be performed by labor having little or no technical knowledge of the requirements of chromium plating, the operation of the machine requiring merely the observance of simple rules, substantial deviation from which will have no injurious effect upon the operator, upon the machine, or upon the article being plated.

The machine illustrated in the accompanying drawings is particularly designed for applying a chromium surface to printing plates, the machine including therein a holder for such plates so constructed as to permit the plating of a single or a plurality of plates simultaneously. This holder is not only so constructed as to facilitate the mounting of plates thereon and their removal therefrom, but the shifting of the holder, in its entirety, from one tank to another when required during the plating operation. During the depositing of chromium, the holder and the plate or plates carried thereby form the cathode of an electrolytic cell, my invention contemplating a construction of the holder by which the surface upon which the chromium is to be deposited is limited to the plate within the holder, no substantial areas of the holder itself, exposed toward the anode, being of electro-conductive material.

Not only does a machine embodying the invention include those agencies by means of which a plate may be prepared for the electro depositing of chromium thereon and the depositing of such chromium, but also agencies by means of which a previously applied surface of chromium may be removed from an article, as when, assuming the article to be a printing plate, wear has occurred upon the surface to an extent to make a re-plating thereof desirable.

The tanks containing the various solutions

for cleaning, washing, plating or stripping a plate are not only so arranged in relation to each other as to permit the withdrawal of a plate holder from one solution and its submersion in another, but are supported at a height to permit a convenient handling of the holder. A movable closure for the space above the tanks is provided, so that the operator may have free access to any tank or be protected from gases or fumes evolved during the plating operation, such being withdrawn from the housing above the tanks as rapidly as they are evolved. Hence when the closure is moved to expose the tanks following the completion of the plating operation, no fumes will escape from the machine.

I also provide in the machine, a special mechanism for connecting metallic chromium anodes to a bus bar.

The invention consists in the novel features of construction and combination of parts hereinafter set forth and described, and more particularly pointed out in the claims hereto appended.

Referring to the drawings,

Fig. 1 is a front perspective view of a chromium plating machine embodying the invention, with the parts in a position to permit the user to ship the plate holder to the required tank, the door being in the open position, partly broken away;

Fig. 2 is a section on the line 2—2 of Fig. 1;

Fig. 3 is a section on the line 3—3 of Fig. 1;

Fig. 4 is a front elevation of the holder for the plate or other article;

Fig. 5 is a side view thereof;

Fig. 6 is a diagram illustrating the electrical conditions in the machine; and

Fig. 7 is a detail view of the anode support.

Like numerals refer to like parts throughout the several views.

A chromium plating machine embodying my invention contains four tanks 10, 11, 12 and 13 arranged side by side within a supporting angle metal frame 14, at a height to position the open tops of said tanks so that the operator may conveniently place a plate holder within any tank or remove it therefrom as required during different stages of the plating operation.

The portion of the frame above the open tops of the tanks is closed by means of the side plates 15 and 16, the back plate 17, a top plank 18 and a door 19 hinged to a brace 20 serving not only as a support for this door, but as a lateral brace for the frame 14.

The frame 14 affords corner braces serving as legs for supporting the machine, the frame being further braced by laterally extended angle metal braces 21 and angle metal top braces 22 extending entirely about the top of the frame, and supporting the top plank 18.

Passing through the plank 18 is the intake pipe 23 of an exhauster 24, the outlet of which exhauster may be connected with a flue leading to, or directed toward an opening communicating with atmosphere. This exhauster is motor-driven and preferably is so wired as to be set in operation simultaneously with the closing of the circuit to the electrodes, whether during the operation of cleaning, plating or stripping, during which operations the door 19 will be closed. Hence all gases and fumes evolved as a result of electrolytic action within the machine will be carried away from the upper portion of the machine so that possibility of the escape of noxious fumes within a workroom, or into the face of an operator upon the opening of the door 19, is prevented. The use of the door 19 also prevents an operator from leaning over the tanks during the plating operation, with resultant irritation of the membranes of the nose and throat resulting from the inhalation of chromic acid fumes. The quantity of hydrogen freed during the electrolytic action is not sufficiently great to introduce fire hazard. The space below the plates 16, 17 and 18 and brace 20, and between the lower edges of these plates and said brace and the various tanks, will permit the effective action of the exhauster.

The tanks 10, 11, 12 and 13 are supported by means of insulating material from T-irons 25 extending laterally of the machine and connected with the back and the front legs of the frame 14, the insulating material consisting of a board 26 upon which the tanks rest.

Said tanks are also insulated from each other by means of headed insulating slabs 27 suspended from the top side edges of adjacent tanks. These insulating slabs not only serve as insulators between the respective tanks, but as insulating supports for a bus bar 28 supporting a carbon electrode 29 in the tank 10, and chromium metal electrodes 30 in the tank 12, thus effectively insulating this bus bar from the tanks, and permitting its adjustment with relation to the front walls of the tanks 10, 12 and 13.

The tank 10 is lined as to the side walls thereof with insulating material such as glass plates indicated at 10^a, the insulation of the bottom of the tank not being required because

of the absence of possible short circuiting at this point. The tank 12 is similarly lined with insulating material 12^a, and the tank 13 has a similar insulating lining 13^a for the front and the side walls thereof, but no lining for the back wall, since this wall is used as a cathode during the stripping operation as will more fully appear hereinafter.

The manner of mounting the several tanks is such as to maintain the outer walls thereof out of electrical connection with the supporting frame 14.

The cathode of the electrolytic cell during the cleaning and depositing operation in the tanks 10 and 12, and the anode during the stripping operation in the tank 14, consists of a plate holder so constructed as to be hung within said tanks with relation to the forward wall thereof, or that wall toward the operator, the effective insulation of said holder from any of these tanks being secured by means of a slab of insulating material, 10^b—12^b—13^b, inserted between each tank and the adjacent portion of the frame 14, these slabs being held in position by the insulating slabs 27 between the tanks, and extending above the top edge of the tanks to an extent to space the supporting member of the holder away from the metal of the tank at this point. This construction has the advantage that when the holder is slipped within the tank, it will be supported from the insulating slab above referred to, and the back of the holder will bear against the insulating lining plate for the inside of the front wall of the tank, and bring the holder and the plates therein into a substantially vertical plane as defined by the inside of the front wall of the tank. This condition is highly desirable both during the cleaning and the plating operations, as it ensures greater uniformity in the electrolytic action throughout the entire surface of the plate or plates, or in the throw of the chromium.

The plate holder above referred to is designed particularly for use in the coating of printing plates or dies wherein the surfaces to be coated are plane surfaces. Furthermore, in the commercial use of such machines, it is desirable to so construct the machine including the tanks and the holder as to permit the coating of a single plate, or the simultaneous coating of a plurality of plates.

A holder for a machine embodying the invention is so constructed as to ensure the effective distribution of the electric current throughout any or all plates which may be mounted in the holder, irrespective of the number of plates. It comprises a sheet metal back plate 31 having permanently secured thereto a terminal bar 32 extending well below the center of said plate and having a cross-sectional area sufficiently great to reduce electrical resistance at this point and afford a sufficient capacity to ensure the effec-

tive distribution of the current throughout the plate. The end of the terminal bar 32 is provided with a binding post 33, or other means of attachment for a flexible conductor wire thereto. If desired, a handhold of non-conductive material may be attached to the terminal bar through the binding post to facilitate the handling of the holder, although the current densities used are so low that the use of this handle is a matter of mere convenience. Furthermore, the operators ordinarily use rubber gloves.

The face of the back plate 31 opposite to that to which the terminal bar 32 is secured, is covered by a plate 35 of vulcanized or other electro non-conductive material, this plate extending from a metallic cleat 36 secured adjacent the top edge of the back plate 31, by means of screws, the lower portion of the plate 35 being secured to said plate adjacent the bottom thereof as by means of screws. The upper portion of said plate 35 is also secured to said metallic back plate 31 by means of screws, thus firmly securing the insulating plate in position. Since no portion of the plate 35 can act either as an anode or a cathode, the depositing of chromium upon any substantial area of the holder is prevented, and the flow of electricity and the resultant chemical reactions are limited to the plates to be coated, or to the clamp bar structure serving the two-fold function of securing the plates in position upon the holder and conducting the current thereto. Four vertical lines of openings 37 extend through the metallic back plate 31 and the facing 35 of the plate holder, the openings in the metallic backing being screw-threaded.

Secured in relation to the insulating plate 35 by means of screws passing therethrough and through the openings 37, is a lower metallic clamp bar 38 which, by reason of the vertical row of openings 37, may be set at any desired height upon the plate 35, according to the number of plates to be coated.

Also adjustably mounted in relation to the back plate 31 and the insulating facing plate 35 is a metallic bar 39 which may be secured in any position with relation to the plates 31 and 35 by means of screws co-operating with the openings 37. Pendant from this bar 39 by means of headed studs 40 passing through openings in said bar, is a clamp bar 41, which clamp bar is capable of sufficient movement with relation to the bar 39 to permit clearance for the insertion and removal of a plate or plates from the holder. The clamp bar 41 is acted upon by the clamp screws 42 mounted in the bar 39 and bearing against the top of said bar 41.

The lower clamp bar 38 is in electrical connection with the back plate 31 through the screws securing it in position in relation thereto and to the facing plate 35. The bar 39 is also in electrical connection with said

back plate 31 by the screws securing it in position in relation thereto and to the plate 35, the clamp bar 41 being in electrical connection through the clamp screws 42 with the bar 39. By using four screws for connecting the bars 38 and 39 with the metallic back plate 31, an effective distribution of the electric current throughout these bars is secured, and the use of a plurality of clamp screws 42 will also have the same effect with relation to the movable clamp bar 41.

The terminal bar 32 carries a hook 43 by means of which the holder in its entirety may be suspended by the engagement of this hook with the insulating slab 10^b, 12^b or 13^b.

The top plank 18 serves as a support for the motor driven exhauster 23, and also for a double throw pole changing switch 44.

Associated with the cabinet or housing within which the tanks 10 to 13 are contained, is a motor generator set 45 and a switchboard 46 having two switches, one of which 47 controls the circuit to the motor of the motor generator set 45, and the other of which 48 controls the lines from the generator of this set.

The contacts of one set of contacts of the switch 48 are connected with the movable contacts of the switch 44 by the leads 49 and 50 respectively.

A detailed description of the switch 44 is unnecessary, as such is old and well known in the electrical art.

One of the offtake contacts 51 of this switch 44 is in electrical connection with the bus bar 28, and with the tank 13, by the lead 52, and the other offtake contact 53 is connected by means of the lead 54 with the terminal bar 32 of the holder.

The door 19 and the top plank 18 are provided with cooperating latch members 55 and 56 of any desired construction for holding this door in the closed position.

In depositing chromium upon the plates, it is desirable, and in stripping it therefrom, it is necessary, to have the solution contained in the tanks 12 and 13 at a temperature above normal. To meet this condition, I provide a gas heater 60 below the tanks 12 and 13, which is so constructed as to bring and maintain the solution within these tanks to approximately the desired temperatures. These temperatures may range from 110° to 130° F., but any variations from these temperatures would not materially modify the operative effects of the machine, provided that such variation is not excessive.

The anodes 30 supported by the bus bar 28 are of pure metallic chromium, and three of such anodes, approximately an inch in width and 12 to 14 inches in length, are used. Owing to the extreme hardness of this metal, I have found it highly desirable to provide a special attachment for mounting same in relation to the bus bar, this special attachment

not only facilitating such mounting of the anodes, but also permitting the use of shorter anodes by spacing the top of the anodes away from the bus bar sufficiently to cause the submersion of the entire length of the anode in the electrolyte. This attachment also firmly holds the anode and acts as a conductor for the electric current passing therethrough. Said attachment comprises a sheet metal yoke 56 secured centrally thereof by means of the bolt 57 to the anode. The inturned ends 58 of this yoke are brought to an edge. Passing through opposite sides of the yoke is a clamp bolt 59. Notches 30^a are ground in the opposite edges of the anode adjacent the top thereof, these notches being so formed as to receive the reduced ends of the yoke. When these parts are in position, the clamp screw 59 is taken up so as to close the yoke tightly upon the anode, thus firmly holding it in position in relation to the bus bar.

The reduced ends 58 and the notches 30^a are used merely to avoid reliance upon frictional engagement of the yoke for suspending the anode in the bath. The material of the yoke is sufficiently flexible to permit the closing of the sides thereof upon the anode in the manner described, and its cross-sectional area and the area of contact between same and the bus bar, is such as to offer no resistance to the electric current in excess of that of the anode itself.

By means of a chromium plating machine embodying the invention, the coating of printing plates may be done by what may be termed "unskilled labor", since the operation requires no technical knowledge on the part of the user, but merely the following of a certain prescribed routine.

Water in an amount determined by the dimensions of the tanks 10 to 13 is first placed in each of these tanks. Approximately a certain amount of an alkaline solution proportionate to the water therein, is then poured into the tanks 10 and 13. Approximately a certain amount of chromic acid solution proportionate to the water therein, is then poured into the tank 12. The solution in the tanks 10, 12 and 13 is then stirred sufficiently to ensure a thorough admixture of the ingredients of the contents of the tanks. The baths are immediately in a condition for use and then require no further attention over a long period of time, although at intervals of say a month or two months, approximately a certain amount of the chromic acid solution may be added to the contents of the tank 12.

The user of the machine first mounts a plate or plates in the holder, the bars 38 and 41 being caused to tightly engage the top and bottom edges of the plate or of a group of plates, as shown in Fig. 4, by taking up the clamp screws 42. This is necessary not only to avoid possible escape of the plates from the holder to within the bath, but to ensure the

proper conduction of the electric current to the plate.

When the plates are properly mounted in the holder and the lead 54 is properly connected with the terminal bar 32, the plate holder is mounted in the tank 10 by placing the hook 43 over the insulating slab 10^b. The movable member of the switch 44 is then thrown so as to positively charge the bus bar 30, and negatively charge the plate holder. The holder with the plates thereon is allowed to remain in the bath of the tank 10 for from three to five minutes, and the holder is then removed from the tank 10 and dipped in the tank 11, which is a mere rinsing tank. After thorough rinsing the holder is removed from the tank 11 and immediately placed in the tank 12 with the hook 43 engaging the insulating slab 12^b. The door 19 is then closed and latched, and the holder is allowed to remain in the bath for about an hour. At the expiration of this time, the switch 44 is used to cut off the flow of current to the bus bar 28, the door 19 is opened, and the plate holder with the plates thereon is then again submitted to the contents of the tank 11 and thoroughly rinsed. The time intervals stated are not at all controlling. No harm results if the plates are left in the tank 10 for a longer interval, and the only result of prolonging the interval during which the plates are in the tank 12, will be an increase in the thickness of the chromium plating. One hour in this tank 12 will give a plating of from .0002 to .0003 of an inch, which is all that is necessary.

While the plates are in the baths in the tanks 10, 11 or 13, no noxious fumes will be evolved. During the electrolytic action, however, in the tank 12, there will be a small evolution of gases from the chromic acid, which, if inhaled by the operator, would cause some irritation of the membranes. The use of the door 19, however, coupled with the action of the exhauster 24 through the pipe 23, will remove all these fumes from the housing above the tanks, and at the same time prevent an operator from attempting to observe the progress of the work, and thus bring his head above the tank 12, where notwithstanding the use of the exhauster, he would inhale some of the fumes. While with a proper solution the quantity of such fumes would have no serious effect upon the operator, the use of the door 19 eliminates any possibility of any objectionable characteristics in the use of a machine due to a theoretical injury to the health of the operators, and makes it possible to use the machine in a workroom occupied by a number of workers, without introducing any hazard to which official objection might be raised.

If it be desired to strip the surfacing from a plate or plates, the same are mounted in a holder in the manner above referred to with plates to be coated, and the holder with the

plates is submerged in the solution in the tank 13. The switch 44 is then thrown to impress a positive current upon the plate holder, and a negative current upon the tank. The time interval required for stripping the plate is but a few minutes.

While I have stated that immediately upon the admixture of the solution in the tank 12 it is ready for the plating operation, it is desirable to raise the temperature of this solution, and necessary to raise the temperature of the solution in the tank 13 prior to the plating operation. The heater 55 is provided for this purpose and the arrangement and capacity of the heater may be such that it will maintain approximately the desired temperature of these baths.

So far as the machine in its entirety is concerned, no technical knowledge is required in its operation. The capacity of the motor generator set is such as to impress a current of the desired density upon the holder whether the same be for cleaning, coating or stripping. The capacity of the exhauster is also predetermined. The various time intervals are merely approximate intervals which if exceeded will do no harm, and if not reached will not materially impair the efficiency of the machine.

30 A machine embodying the invention has been successfully operated by unskilled men with entirely satisfactory results.

The presence of the insulating lining upon all sides of the tanks 10 and 12, and upon the front and opposite sides of the tank 13, permits continued operation of the machine without electrical difficulties which will impair its efficiency in any way.

In fact with a machine embodying the invention, the surfacing of plates with chromium becomes merely the doing mechanically by the operator of certain things for approximately certain intervals, and the repeated following of the same practices will give substantially uniform results. The solutions used of course may be varied, but with certain solutions uniform results secured by the machine are assured without any attention of the operator whatever to the baths beyond the occasional addition of the active ingredients of the electrolyte.

The presence of the facing 35 of insulating material will limit the deposit of chromium upon the plate or plates carried by the holders. If only a single small plate is to be coated, this is of advantage as it not only prevents accretion of chromium upon the holder with continued use of the machine, but limits the consumption of the bath to the requirements in coating plates.

Of course the vertical dimensions of the holder must be such as to avoid contact of the plate 31 with the bottom of the tanks, which are not insulated since there is no tend-

ency for a short circuiting of the current at this point.

It is not my intention to limit the invention to the precise details of construction shown in the drawings, or to the exact dimensions of the tanks and the plate holder as herein stated, it being apparent that such may be varied to adapt the machine to plates of different sizes.

Having described the invention, what I claim as new and desire to have protected by Letters Patent, is:—

1. A chromium plating machine embodying therein adjacent tanks adapted respectively to receive a cleaning, a rinsing and a plating bath, a holder for articles to be plated, means supporting said tanks with the open tops thereof at a height to permit the convenient transfer of said holder from one tank to another, fixed means forming a housing above said tanks having a closed top and an opening at the front thereof through which access may be had to said tanks, movable means for closing said opening, a flexible conductor placing said holder in connection with an electrical source, means insulating said tanks from the means supporting same and from each other, a bus bar common to, and insulated from, said tanks containing the cleaning and plating baths, anodes carried by said bus bar and submerged in said cleaning bath and said plating bath respectively, and means for withdrawing fumes from within said housing.

2. A chromium plating machine embodying therein adjacent tanks adapted respectively to receive a cleaning, a rinsing and a plating bath, insulating linings extending entirely about the inner walls of the tanks containing the cleaning and the plating baths, a holder for articles to be plated, means supporting said tanks with the open tops thereof at a height to permit the convenient transfer of said holder from one tank to another, fixed means forming a housing above said tanks having a closed top and an opening at the front thereof through which access may be had to said tanks, movable means for closing said opening, a flexible conductor placing said holder in connection with an electrical source, an insulating slab projecting above the open tops of said tanks containing the cleaning and the plating baths, means carried by said holder adapted to engage said insulating slab and hold the back of said holder in substantially parallel relation with the insulating lining of the front wall of the tank, and out of electrical connection with the tank, means for insulating said tanks from the means supporting same and from each other, a bus bar common to, and insulated from, said tanks containing the cleaning and plating baths, anodes carried by said bus bar and submerged in said cleaning bath and said plating bath respectively, and means for

120
125
130

withdrawing fumes from within said housing.

3. A chromium plating machine embodying therein adjacent tanks adapted respectively to receive a cleaning, a rinsing and a plating bath, insulating linings extending entirely about the inner walls of the tanks containing the cleaning and the plating baths, a holder for articles to be plated, means supporting said tanks with the open tops thereof at a height to permit the convenient transfer of said holder from one tank to another, fixed means forming a housing above said tanks having a closed top and an opening at the front thereof through which access may be had to said tanks, a brace bar adjacent and below the open tops of said tanks, a door hinged upon said brace bar, means for holding said door in the closed position, a flexible conductor placing said holder in connection with an electrical source, an insulating slab projecting above the open tops of said tanks containing the cleaning and the plating baths, means carried by said holder adapted to engage said insulating slab and hold the back of said holder in substantially parallel relation with the insulating lining of the front wall of the tank, and out of electrical connection with the tank, means insulating said tanks from the means supporting same and from each other, a bus bar common to, and insulated from, said tanks containing the cleaning and plating baths, anodes carried by said bus bar and submerged in said cleaning bath and said plating bath respectively, and means for withdrawing fumes from within said housing.

4. A chromium plating machine embodying therein adjacent tanks adapted respectively to receive a cleaning and a plating bath a holder for articles to be plated, means supporting said tanks with the open tops thereof at a height to permit the convenient transfer of said holder from one tank to another, fixed means forming a housing above said tanks having a closed top and an opening at the front thereof through which access may be had to said tanks, movable means for closing said opening, means insulating said tanks from the means supporting same and from each other, a bus bar, an anode carried by said bus bar and submerged in said plating bath, and means for withdrawing fumes from within said housing.

55 In witness whereof I have hereunto affixed my signature this 20th day of October, 1926.

WILLIAM S. EATON.
